HANDBAG OR SIMILAR ARTICLE

Gladys Murray, New York, N. Y., assignor to Bernard Cahn Co., Inc., New York, N. Y.

Application December 12, 1957, Serial No. 48,884

Term of patent 7 years

(Cl. D87—3)

I claim:

The ornamental design for a handbag or similar article, substantially as shown.
